UNITED STATES PATENT OFFICE

2,471,467

ESCAPE DEVICE

Le Roy L. Werner, Washington, D. C.

Application April 4, 1945, Serial No. 586,617

4 Claims. (Cl. 292—340)

(Granted under the act of March 3, 1883, as
amended April 30, 1928; 370 O. G. 757)

1

The invention described herein, if patented may be manufactured and used by or for the Government for governmental purposes, without the payment to me of any royalty thereon.

The present invention relates to escape devices generally, but is particularly intended for use in conjunction with refrigerators, safes, or other receptacles in which a person might be confined, either intentionally or otherwise, by the closing of the door and the operation of the latch, lock, or other securing device.

It is a primary object of the invention to provide a release mechanism operable from the interior of the receptacle, and which is associated with the door lock or latch in such manner that the operation of the release device will render the locking means ineffective.

Another object of the invention resides in the provision of a removable panel or plate on the door, on which is mounted one of the elements of the lock or latch, and means accessible from the interior of the container for releasing the plate and thereby render the lock ineffective.

Other objects and advantages of the invention will be apparent from the following description when taken in connection with the accompanying drawings, in which,

Figure 1 is an elevational view of a door with one of the escape devices installed therein.

Figure 2 is a sectional view taken on line 2—2 of Figure 4, looking in the direction of the arrows.

Figure 3 is an interior elevational view of the escape device, and

Figure 4 is an enlarged vertical sectional view taken on line 4—4 of Figure 1.

Referring to the drawings in greater detail, the numeral 1 indicates a portion of the wall of a commercial refrigerator, safe or other container of sufficient size to permit the entry of attendants. Numeral 2 indicates a door mounted upon vertically spaced hinges 3 and provided with a conventional latch 5 and keeper 6, the former co-operating through its shaft 5' with latch element 5'.

In the embodiment shown, the escape device is shown as installed in a refrigerator and consequently the door is relatively thick to provide space for such heat insulating material as may be necessary. Within this space is mounted a wood block 7 to the front face of which is attached a circular casing or bracket member 8 which encircles the area surrounding the location of the keeper 6. The outer wall of the door 2 is

2

plate the keeper 6 is supported and may be welded thereto or otherwise connected as desired. Projecting from the inner surface of the panel 10 are a centrally disposed bolt 11 and pins 12 adapted to be passed through closely fitting apertures in the body of the door to prevent rotation of the plate.

Between the plate 10 and the outer face of the door 2 is inserted a gasket 13, and an arched plate 14 is mounted upon the bolt 11 and pins 12 as indicated in Figure 4. The bolt 11 is threaded on its inner end for the reception of a wing nut or the like 15 which serves to draw the plate 14 toward the plate 10 to thereby clamp the keeper element 6 in its operative position on the outer face of the door. The plate 14 may be provided with finger openings 16 to permit ready removal of the plate when necessary.

The block 7 is provided with a central opening 20 in line with the securing means for the keeper or latch element 6 so as to permit access to these elements from the interior of the refrigerator or other container. This opening is indicated by the numeral 17 which may be closed by a plug of insulating material 18, and in conjunction with the opening 9 and circular casing 8 provides an elongated passage extending from the exterior to the interior of the container. A gasket 19 forms a seal between the plug 18 and the block 7 and a pivoted handle 20 on the plug is provided with offset extensions 21 adapted to enter slots 22 in a rim 23 so as to provide a bayonet joint connection for the plug.

In the operation of the escape device, a person locked within the refrigerator or other container, either accidentally or by design, could readily obtain his release by merely removing the plug 18, and then removing the wing nut 15 and arched plate 14. With these parts removed it is readily apparent that the plate 10 which supports the keeper 6 may be moved outwardly, thereby operating the latch member 5 and permitting the door to be opened by pressure from within the container 1.

While in the specific embodiment shown the keeper or latch member 6 is mounted upon the removable plate 10 on the door, it will be quite obvious that the invention is not so limited inasmuch as the keeper could be placed upon the body portion of the receptacle in a reversal of the latch mechanism.

In accordance with the patent statutes, I have described what I now consider to be the preferred

may be made in the details of construction and the relation of the parts without departing from the spirit of the invention, and it is accordingly intended that all such variations be included within the scope of the appended claims.

What I claim is:

1. An escape device for containers comprising a body portion and a door, said container provided with an elongated passage extending to the interior and exterior thereof, an imperforate panel, a latch element fixed to the exterior face of the panel, said panel being mounted exteriorly of the container and closing the outer end of said passage, a plate within the passage, and means also within the passage and cooperating with the plate for drawing said panel and plate into clamping relationship with the container.

2. An escape device for a container comprising a body portion and a door, said container provided with an elongated passage extending to the interior and exterior thereof, an imperforate panel mounted on the outside of the container and closing the outer end of said passage, a bolt fixed to the inner face of the panel and extending into the passage, a latch element on the exterior face of the panel, and means wholly within the passage for cooperating with the bolt to clamp the imperforate panel in operative position.

3. An escape device for a container comprising a body portion and a door, said container provided with an elongated passage extending to the interior and exterior thereof, an imperforate panel mounted on the outside of the container and closing the outer end of said passage, a bolt fixed to the inner face of the panel and extending into the passage, cooperating means on the panel and

container wall to prevent rotation of the former, a latch element on the exterior face of the panel, and means wholly within the passage for cooperating with the bolt to clamp the imperforate panel in operative position.

5. An escape device for a container comprising a body portion and a door, said container provided with an elongated passage extending to the interior and exterior thereof, an imperforate panel mounted on the outside of the container and closing the outer end of said passage, a bolt fixed to the inner face of the panel and extending into the passage, a plate within the passage, and means also within the passage and cooperating with the plate for drawing said panel and plate into clamping relationship with the container.
